CLAIM

The ornamental design for a shoe ornamentation, as shown and described.

DESCRIPTION

FIG. 1 is a rear view of a shoe ornamentation showing my new design;

FIG. 2 is a bottom view of the design shown in FIG. 1;

FIG. 3 is a right side view of the design shown in FIG. 1;

FIG. 4 is a left side view of the design shown in FIG. 1;

FIG. 5 is a top view of the design shown in FIG. 1; and,

FIG. 6 is perspective view of the design shown in FIG. 1.

The elements shown in broken lines show environmental structure and are for illustrative purposes only forming no part of the claimed design.

FIGS. 1-6 depict views of a right shoe showing my new design. Respective views of a left shoe showing my new design are mirror images thereof.
